(57) CLAIM

The ornamental design for a nose hair trimmer, as shown and described.

DESCRIPTION

FIG. 1 is a perspective view of a nose hair trimmer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of FIG. 1 in a second state, shown with an unclaimed cap.

The broken lines in the drawings are for the purpose of illustrating portions of the nose hair trimmer that form no part of the claimed design.
